PLASTER LATH

Filed March 5, 1924

INVENTOR.

John F. Makowski

BY *Henry J. Webster*

ATTORNEY

UNITED STATES PATENT OFFICE.

JOHN F. MAKOWSKI, OF STOCKTON, CALIFORNIA, ASSIGNOR TO CALIFORNIA CEDAR PRODUCTS COMPANY, OF STOCKTON, CALIFORNIA, A CORPORATION.

PLASTER LATH.

Application filed March 5, 1924. Serial No. 697,050.

To all whom it may concern:

Be it known that I, JOHN F. MAKOWSKI, a citizen of the United States, residing at Stockton, county of San Joaquin, State of California, have invented certain new and useful Improvements in Plaster Laths; and I do declare the following to be a full, clear, and exact description of the same, reference being had to the accompanying drawings, 10 and to the characters of reference marked thereon, which form a part of this application.

This invention relates to the building art and particularly to wall construction.

15 The object of the invention is to produce a plaster lath of the type described in my allowed application for patent, Serial No. 608,595, the design of the present invention being to develop a very cheap form of lath 20 which will find a ready demand due to the decreased cost thereof.

In developing a cheap lath however the fact must not be lost sight of that the lath must be impervious to moisture and the finely 25 divided mineral fragments must nevertheless be securely adhered to the surface of the base board. I believe that in the herein described form of lath I have accomplished both objects.

30 The drawing is a section of the plaster lath.

Referring to the numerals on the drawings, 1 designates the base board. Over the surface of the board I spread, by any suitable 35 means, a coating consisting of silicate of soda and water of a desired consistency. This silicate of soda provides a very cheap binder or adhesive for adhering the finely divided mineral fragments to the base board.

40 It is not however impervious to moisture but

is readily soluble. This would of course render the lath non-commercial.

Therefore, after the mineral fragments 3 are spread over the coating 2, I then spray 45 the entire surface with a dilute solution of casein and lime. The lime acts as a temporary solvent for the casein.

When the entire board dries the silicate of soda, as indicated, forms a cheap and efficient binder for the mineral fragments. The 50 casein, after drying, forms an insoluble water proof coating 4 over the surface of the lath. Thus I am enabled to produce a cheap lath and yet one which is water proof and therefore usable commercially. 55

I have given herein the preferred embodiment of the invention. However, such deviations therefrom may be made as may fall within the scope of the appended claims.

Having thus described my invention what 60 I claim as new and useful and desire to secure by Letters Patent is:

1. A plaster lath comprising a base, a coating of silicate of soda over the surface of the base, finely divided mineral fragments 65 adhered to the base, and an insoluble coating over the surface of the lath.

2. A plaster lath comprising a base, a coating of silicate of soda over the surface of the base, finely divided mineral fragments 70 adhered to the base, and a coating over the surface of the lath consisting essentially of casein.

3. In a plaster lath of the type set forth in which the finely divided mineral fragments 75 are adhered to the base by a soluble binder, of a coating of insoluble material spread over the surface of the lath.

In testimony whereof I affix my signature.
JOHN F. MAKOWSKI.
